UNITED STATES PATENT OFFICE.

FRANK F. PYLECK, OF CLEVELAND, OHIO.

PORTABLE WARDROBE.

Application filed April 16, 1924. Serial No. 706,908.

To all whom it may concern:

Be it known that I, FRANK F. PYLECK, a citizen of the United States, and resident of Cleveland, in the county of Cuyahoga and

5 State of Ohio, have invented new and useful Improvements in Portable Wardrobes, of which the following is a specification.

This invention relates to wardrobes and more particularly to that class of portable 10 wardrobes which can be used for stores, assembly halls, homes, etc.

The object of this invention is to provide a portable wardrobe which can be shipped in a knocked down condition, and which can 15 be easily assembled.

Another object of the invention is to provide a novel wedge to lock and unlock the parts.

Still another object of this invention is 20 to provide a novel means of gripping and hanging the curtain.

Other objects will appear as the disclosure progresses. The drawings are intended merely to indicate a possible embodiment 25 of the invention. It is obvious that the actual needs of manufacture may necessitate certain mechanical changes. It is, therefore, not intended to limit the invention to the embodiment illustrated, but rather, to 30 define such limits in the appended claims.

In general, the device consists of two up-right legs, a tray at the bottom, an intermediate brace, an upper tray, and a bar to support a curtain.

35 For a more detailed understanding of the invention, attention is now called to the drawings in which a preferred embodiment is shown illustrated. In these drawings, like parts are designated by like reference 40 characters in all the views.

Figure 1 is a front elevation of the novel wardrobe.

Figure 2 is a side view thereof.

45 Figure 3 is a top view thereof with the curtain removed.

Figure 4 is a detail, showing the wedge in cross section.

Figure 5 is a front elevation of the wedge.

50 Figure 6 is a section on line 6—6 of Figure 5.

Figure 7 is an elevation of one of the legs.

Figure 8 is an elevation of the floor of the bottom tray.

55 Figure 9 is a view of the cross piece supporting the upper tray.

Figure 10 is a section on line 10—10 of Figure 1.

Figure 11 is a side view of the curtain grip.

Referring now to the drawings in detail, 60 numeral 1 designates the legs or upright members, 2 a bottom tray, 3 the floor of the bottom tray, 4 an intermediate brace and 5 a cross piece to support an upper tray 6.

In the upright members 1, holes 7 are provided into which the ends 8 of the brace 4 and cross piece 5 fit. The lower ends of the upright members 1 have narrowed portions 9 which fit into cut-out portions 10 of the feet 11.

70 At the corners of the bottom tray 3, projections 12 are provided having square holes 13 therein. These projections 12 fit into holes of the feet 11 and are locked in place by wedges 14. Holes are also provided in 75 the cross piece 5 and in the intermediate brace 4, for the wedge 14 to slip in for locking the wardrobe in place.

80 In the upper ends of the upright members 1, grooves 15 are provided in which is supported a curtain rod 16. This rod, as noted in Figure 10, is made of sheet metal bent over in the shape of a T. Slidably attached on the rod 16 are grips 17 to hold the curtain 18 in place. The grip 17 consists of two members 19 and 20, bulging outwardly at 21, having a neck 22 and flared outwardly at 23. Numeral 25 represents two lower ends urged outwardly by a spring 26, and pivotally connected at 24.

85 The compression in the spring is sufficient to grip the two ends 27 of the curtain 18 firmly in place. To release the curtain, the two ends 25 are brought together. The curtain 18 is formed in four sections and meet 90 in the center, and can be spread apart (as the grips 17 are slidable) to have access to the trays 2 and 6.

95 Hooks 28 are provided to hang clothes thereon, and to the inside of one of the up-right members 1, C-shaped members 29 are attached to support umbrellas in an upright position.

100 The novel wedge consists of two members 30 and 31 pivoted at 32 and urged outwardly by a spring 33 near the opposite end. The ends 34 are tapered for easy access in the holes, and cut-out portions 35 are provided to lock the wedge in place. To remove the wedge, the two ends 38 are brought together 110

and the wedge will then be in a position to slip out of its hole.

The upper tray can be used for hats and the lower tray for shoes. The material of this device can be of any nature to suit the needs of manufacture.

The structure and operation of this novel device has now been fully set forth.

What I desire to secure by United States Letters Patent is:

1. In a device of the class described in combination, two upright members attached to feet at the lower ends, a bottom tray, an intermediate brace, an upper cross piece, an upper tray, cutout portions in the said upright members into which the ends of the said intermediate brace and upper cross piece fit, square holes in the ends of the said intermediate brace and upper cross piece for a wedge to fit into, a floor for the lower tray having projections and square holes at the corners for a wedge to fit into, a groove at

the top of the said upright members to support a curtain rod, and wedges to keep said upright members in place, the said wedges being composed of two members internally pivoted at one end, a spring to urge the other end outwardly, the last mentioned end being tapered on the outside upper and lower surfaces, and a groove for the said wedge to lock itself in position.

2. In a device of the class described in combination, upright members, a wedge to lock the said upright members in place, the said wedge being composed of a male and female member internally pivoted at one end, a spring to urge the other end outwardly, the last mentioned end being tapered on the outside upper and lower surfaces, and a groove for the said wedge to lock itself in position.

In testimony whereof I affix my signature.

FRANK F. PYLECK.
